Fig. 1

The characteristic features of my design for the front for eyeglasses disclosed reside in the surface ornamentation on the face portions thereof as shown.

I claim:

The ornamental design for a front for sunglasses or the like, as shown and described.
